UNITED STATES PATENT OFFICE.

CHARLES M. ADAMS, OF PROVIDENCE, RHODE ISLAND.

MECHANICAL PIN-CASE.

SPECIFICATION forming part of Letters Patent No. 366,059, dated July 5, 1887.

Application filed April 30, 1887. Serial No. 236,629. (No model.)

To all whom it may concern:

Be it known that I, CHARLES M. ADAMS, a citizen of the United States, residing at Providence, in the State of Rhode Island, have invented a new and useful Improvement in Mechanical Pin-Cases, of which the following is a specification.

The nature of my invention consists in an improved pin-case having a receiving-hopper, from which one pin at a time is raised and carried to a stop-guide, and raised from thence by means of the alternately-reversed movement of the mechanism, as hereinafter fully set forth.

Figure 1 represents a central vertical section, with a portion of the side of the box broken away in order to show the mechanism for agitating the hopper, the raised pin being held in position for presentation. Fig. 2 is a similar section showing the position of the several parts of the mechanism when the pin is being seized for presentation. Fig. 3 represents a top view of the box with the cover removed, showing a portion of the operating mechanism, the pin-presenting portion being also removed.

In the accompanying drawings, A is an ornamental box, which may form a portion of a lady's dressing case. B is a rectangular frame, provided with the ears *a a*, which are adapted for attachment to the cover C of the box by means of screws. To the end *b* of the frame B is secured the hopper D, which may have its inclined bottom *c* and turned-up end *d* made of sheet-steel or hard rolled brass, and so set that the hopper, when secured to the frame B by the turned-up end *d*, will spring upward toward the frame. Through pendent ears *e e* at opposite sides of the frame B is placed the rock-shaft E, upon the outer end of which, beyond the side *f* of the box, is secured the milled head F, by turning which in opposite directions the mechanism for picking up the pin and presenting the same is operated. To the shaft E, and centrally of the hopper D, is secured the picking-arm G, which upon its

downward movement strikes into the corner *g* of the hopper, and is provided with a lip, *h*, and an opposite spring-lip, *i*, secured to the upper end of the arm G, and provided with the notch *j*, adapted to hold the pin; and in order to prevent holding engagement with two or more pins at the same time, I provide a stud

or pin, *k*, secured to the lip *h* and passing loosely through a perforation in the spring-lip *i*, so that the pins in the hopper cannot pass inward beyond the stud *k*, thus restricting the 55 engaging lips *h* and *i* to a single pin. Upon the shaft E is also placed the cam H, which, by striking against the projecting end of the stud *l*, attached to the bottom of the hopper, serves to agitate the said hopper, so that the pins 60 which are dropped promiscuously through the opening I will be caused to arrange themselves transversely of the picking-arm G in a parallel position at the angle *g* of the hopper. The picking-arm is limited in its upward and back- 65 ward movement by the stop-bar *m*, and the downward movement of the same will be limited by the pile of pins in the hopper. The outer end of the shaft E is bent to form a crank-arm, J, from which connection is made to the 70 crank-arm K of the rock-shaft L by means of the connecting-rod M. The rock-shaft L is journaled in the opposite sides of the frame B, and upon the shaft L, between the opposite sides of the frame B, is secured the tube N, 75 (shown in section in Fig. 3,) upon which is placed the bird O or other suitable device for picking up and presenting the pin. The under portion, *u*, of the bill of the bird is pivoted at *o*, and is operated to hold the pin *p* by means 80 of the spring *q*, as shown in Fig. 2. The upwardly-bent arms *r r*, which form the stop-guide, are secured to the cross-bar *m* and provided with the shoulders *s s*, against which the pin raised from the hopper is deposited upon 85 the upward and backward movement of the picking-arm G, the projecting lips *t t* serving to prevent the pin from dropping away or moving from the shoulders. The openings *v v'* in the cover C of the box are closed by means of the 90 slotted plates *w w* and *x*.

The operation is as follows: A suitable quantity of pins having been placed in the hopper D through the opening I, the movement of the shaft E in the direction to throw the picking-arm G downward upon the pins in the hopper will cause one of the pins to be caught in the notch *j* between the lips *h* and *i*. The movement of the shaft E is then to be reversed, which reverse movement will cause the picking-arm G to be raised and carried back until the pin held in the notch *j* strikes against the 95 100

shoulders *s s* of the arms *r r* of the stop-guide, thus causing the pin *p* to be drawn from the notch *j* and be held upon the projecting lips *tt* against the shoulders *s s*, and the continued 5 backward movement of the picking-arm *G* will be limited by the stop-bar *m*. The latter movement of the shaft *E* will also cause a corresponding movement of the shaft *L*, thus bringing the bird *O* forward and downward, so that 10 its bill *R* will embrace the middle portion of the pin *p* while the same is yet in the notch *j* of the lips *h* and *i*, and by springing thereon will serve to firmly hold the same upon the reverse movement of the shaft *E*, which will 15 cause the bird *O* to be brought back to the position shown in Fig. 1, with the pin in its bill for proper presentation for use, and as often as the above-described alternate movements are made pins will be raised from the hopper and 20 be presented by the bird until the hopper is emptied of the same.

I claim as my invention—

1. The combination, with the hopper, of vibrating means for picking up the pins in the hopper, the stop-guide for receiving the pin 25 from the picking means, and the presenting means operatively connected with the picking means, substantially as described.

2. The combination, with the hopper and means for vibrating the same, of means for 30 picking up the pins in the hopper, the stop-guide for receiving the pin from the picking means, and the presenting means operatively connected with the picking means, substantially as described.

CHARLES M. ADAMS.
